UNITED STATES PATENT OFFICE.

JAMES R. WAY, OF BUFFALO, NEW YORK, ASSIGNOR TO THE PIERCE-ARROW MOTOR CAR COMPANY, OF BUFFALO, NEW YORK.

DESIGN FOR A RADIATOR-FRAME FOR AUTOMOBILES AND OTHER VEHICLES.

53,228.

Specification for Design.

Patented Apr. 22, 1919.

Application filed January 8, 1919. Serial No. 270,215. Term of patent 14 years.

To all whom it may concern:

Be it known that I, JAMES R. WAY, a citizen of the United States, residing at Buffalo, in the county of Erie and State of New York, have invented a new, original, and ornamental Design for Radiator-Frames for Automobiles and other Vehicles, of which the following is a specification.

In the accompanying drawings:

Figure 1 is a front elevation, Fig. 2 a side elevation, and Fig. 3 a perspective view of

a radiator frame for automobiles and other vehicles showing my design.

I claim:

The ornamental design for a radiator frame for automobiles and other vehicles, substantially as shown.

JAMES R. WAY.

Witnesses:

D. C. SHAMP,
MILTON H. ALLEN.
